V. MAUCK

APPARATUS FOR EXCHANGE OF HEAT

Filed Sept. 13, 1926.

FIG. I.

FIG. II.

INVENTOR:
VICTOR MAUCK,
by J. Ernest Raige,
Attorney.

UNITED STATES PATENT OFFICE.

VICTOR MAUCK, OF MERION, PENNSYLVANIA.

APPARATUS FOR EXCHANGE OF HEAT.

Application filed September 13, 1926. Serial No. 134,964.

My invention is adapted for inclusion in a house heating system wherein a gas consuming heater unit is connected by pipes with a distant radiating unit or units for heating respective rooms or any inclosure in which such a radiator may be located; both heating and radiating units being preferably of what is known as "honeycomb" or similar cellular construction; and said system including means for maintaining a forced circulation of both water within the heating system and the air heated by the radiator; such circulations being respectively effected by a pump and fans; both preferably operated by electric motors, with thermostatically operative controlling means.

My copending application Serial No. 189,090 filed May 5, 1927, includes claims for the water heater herein contemplated, and my copending application Serial No. 189,091 filed May 5, 1927, includes claims for the heat distributing apparatus herein contemplated; both of said applications being divisions of this application, wherein the claims are restricted to specific features of construction and arrangement of radiating devices and their appurtenances.

My invention includes the various novel features of construction and arrangement hereinafter more definitely specified.

In said drawings; Fig. I is a fragmentary front elevation of a radiator unit as mounted in a ceiling or other wall.

Fig. II is a sectional view of said radiator unit, partly in elevation.

In said figures; the radiator cellular structure 1 includes a congeries of primarily cylindrical flue tubes 2, preferably made of thin sheet copper, and having their opposite ends 3 expanded to hexagonal form so as to fit tightly together with their intermediate cylindrical portions in proper spaced relation to afford passageways 5 between them for hot water or steam. Said flue tubes 2 are assembled within the cylindrical circumferential casing 6 conveniently with circular series of six filling pieces 8 at each of the axially opposite ends thereof. Said radiator structure is provided with opposite side conduits 9 and 10. Said conduits are respectively provided with couplings 11, adapted for detachable connection with the respective pipes 12 and 13 through which the heating fluid is circulated in the passageways 5, in connection with the heater of the system above contemplated.

Said radiator structure is provided with the fan 14 and the motor 15; the latter being preferably mounted within the circular inner casing 16 of the radiator structure in concentric relation with said casing 6, and within a soft rubber band 17 which minimizes the transmission of vibrations from the fan and the motor. Said casing 6 is, preferably detachably, rigidly connected with the face plate 18 which is, preferably detachably, rigidly connected with the outer casing 19 which is adapted to fit in a recess 20 of a ceiling 21, but may be set in any wall substantially flush therewith.

The zone 23 of said face plate 18 is perforated or otherwise made foraminous so as to admit air to the inner side of the radiator structure through the space between the latter and said outer casing 19; which air is driven outwardly by the rotation of said fan 14 through the tubes 2, wherein the air absorbs heat from the hot water or other heating fluid in the passageways 5.

The construction and arrangement of the radiator and its appurtenances above described are such that they may be readily installed; the pipes 12 and 13 being conveniently formed of soft copper tubing and the couplings 11 being conveniently of what is known as the "pinch" type; the joints between them and said pipes being sealed by soft metal bands encircling the pipes, which are pinched between axially opposite complementary conical seats respectively in said couplings and the conduits with which they are in screw threaded engagement.

Although I referred to the apparatus aforesaid as included in a water heating system; it is to be understood that the heated water may be discharged from the heater and presented at the radiators in the form of steam; with the advantage that a greater efficiency per unit of apparatus is thereby attained as compared with apparatus in which the water is continually maintained below its boiling point.

Moreover, I find it convenient to provide a thermostatic device 25 arranged to control the operation of said motor 15, in accordance with the temperature of the air circulated by said fan 14; which device may be a thermostatically operative electric switch included in the circuit of said motor but more or less remote from the latter.

Although I prefer to effect forced circulation of the air with respect to the heat-

ing surfaces of the radiators aforesaid, by means of electrically actuated fans; other means for effecting such circulation may be employed and, in fact, such circulating means may be omitted and the air circulated by convection.

Therefore, I do not desire to limit myself to the precise details of construction and arrangement herein set forth, as it is obvious that various modifications may be made therein without departing from the essential features of my invention, as defined in the appended claims.

I claim:

15 1. In a heating system, a radiator of cellular structure, formed of thin sheet metal walls, forming passageways for air; of a casing exterior to said radiator, in spaced relation therewith; and means arranged to 20 effect the forced circulation of air between said casing and radiator and through the latter.

2. In a heating system, a radiator of cellular structure, formed of thin sheet metal walls, forming passageways for air; of a casing exterior to said radiator, in spaced relation therewith; and means arranged to 25 effect the forced circulation of air between said casing and radiator in one direction, and through the radiator in the opposite direction.

3. A heating system, as described in claim 2; wherein the circulating means is an elec-

tric motor; and a thermostat arranged to control the operation of said motor.

4. In a heating system, the combination with a radiator of cellular structure, formed of thin sheet metal walls, arranged as passageways for air; of a casing for said radiator, having an annular wall in spaced relation with said radiator, and a face plate having a foraminous area between said radiator and casing; said face plate being arranged to extend substantially flush with a building wall, in which said casing extends.

5. In a heating system, as described in claim 4; means arranged to circulate air inwardly through said foraminous area and outwardly through said radiator, including a fan in said casing, behind said radiator.

6. In a heating system, as described in claim 4; means arranged to circulate air inwardly through said foraminous area and outwardly through said radiator, including a fan in said casing, behind said radiator; a motor arranged to actuate said fan; and a thermostat arranged to control the operation of said motor, in accordance with the temperature of the air circulated by said fan.

In testimony whereof, I have hereunto signed my name at Conshohocken, Pennsylvania, this twenty-seventh day of August, 1926.

VICTOR MAUCK.
